GAS DISCHARGE LAMP

Miles Pennybacker, Westport, Conn.

Application December 23, 1944, Serial No. 569,488

8 Claims. (Cl. 176—122)

1

This invention relates to electrical lamps of the gaseous discharge type, more especially to lamps of this type employing a positive column gas discharge and producing light having wave lengths either within or without the visible spectrum.

This invention employs a novel starting conductor between electrodes, similar in some respects to the starting conductor described in United States Patent #1,961,617 but employing on the conductor a coating or surface material of relatively high electrical resistance and permeable to the negative glow discharge.

Positive column gas discharge lamps are usually constructed in the form of a relatively long and narrow cylinder of glass, quartz or other suitable transparent material, provided with suitable electrodes at both ends thereof. In one widely used form, the internal surface of the transparent envelope is coated with a phosphor, which acts to transform luminous energy from one portion of the spectrum, such as ultra violet, to another portion of the spectrum better suited for general illuminating purposes.

For most purposes, it is desired that the light from a lamp be emitted over an arc of not exceeding 180 degrees. Accordingly, when a cylindrically-shaped lamp is employed, it is usually found necessary, or at least highly desirable, to employ a reflector which will render available a portion of the light otherwise wasted by reason of the fact that it is emitted in an undesired direction.

It is thought unnecessary here to describe in detail the operation of starting conductors, as they are well known.

Prior art conductors designed to facilitate starting by having a negative glow spread along their conducting surface, have the disadvantage and limitation that, if they are narrow enough to cause the glow to spread at the desired low starting currents they are susceptible to deleterious changes in width or length, due to sputter. Also, when the surface is an unobstructed conductor, it is liable to carry enough current, as the voltage approaches that necessary to start the main positive discharge, to cause objectionable localized heating at least at one end of the starting conductor. This is true particularly if the positive column path is long, or of relatively high resistance, as in a fluorescent lamp used at low ambient temperature, before the mercury has vaporized, or during the processing of the tube as a manufacturing step. Furthermore, especially if the conductor is of greater surface area per unit of length, it is liable to carry too much of the normal

2

tube current. If the material of the strip has a very high work function, in order to minimize this starting current, then the voltage necessary to initiate flow of current to the conductor is raised to an undesirable value.

One object of this invention is to make possible the construction, over a wide range of dimensions and of various different materials, of a starting conductor or strip, by providing a coating which will cause the negative glow to spread substantially along the length of the starting strip at very small currents and thus will facilitate starting the positive column discharge at lower currents and voltages than would be required with uncoated starting strips of the prior art.

Another object is to provide starting conductors of much greater cross-sectional area, thereby improving their durability, facilitating their handling and mounting in the tube, and permitting their additional use as reflectors or as fluorescent surfaces for transformation of the wave lengths of the luminous output, whereby the overall effectiveness of the tube as a light source is improved, in addition to the above-described improvements in starting characteristics.

Another object of this invention is to provide a novel form of elongated cylindrical lamp from which the externally available light is emitted substantially wholly along one longitudinal half 30 of the cylinder, thus causing the luminous output of the lamp to be completely available without the need of employing a reflector.

Another purpose of this invention is to provide a tubular lamp with an internal reflector, in the form of an element not closely connected, either mechanically or chemically, with the internal wall of the tube, in distinction from reflecting elements which have hitherto been formed as metallic deposits, or the like, upon such internal wall, and 40 which also acts as a starting strip, and optionally also as a support for a fluorescent coating, although this invention may also be practiced with the use of a starting strip of the deposited type.

A still further purpose of this invention is to provide a tubular lamp in which the reflector or starting strip can be manufactured independently of the tube and only inserted therein when the tube is ready to be sealed.

When positive column gas discharge tubes are 50 to be started, it has been found necessary to apply to such tubes a starting potential in excess of the potential existing between electrodes when the positive column discharge has once been established.

55 In order to reduce the starting potential re-

quired in a cold cathode tube, it has been proposed to employ a starting strip. Such strip usually is in the form of a conductor extending from the region near one electrode to the region near the opposite electrode. Such starting strip operates by the establishment of a cathode glow discharge at one or both ends of such strip, and at the portion of one or both of the electrodes adjacent to the strip. The initiation of a cathode glow discharge tends toward increased ionization, which latter effect promotes the establishment of a positive column discharge at a lower voltage. In some proposed forms of starting strip, the cathode glow spreads along the strip, with increasing rise in potential, until the current eventually selects the path of a positive column discharge between the electrodes, as constituting the path of least resistance. This process is described in detail in United States Patent #1,961,617, previously referred to. After the establishment of the positive column discharge, it is highly desirable that all discharge through the path including the starting strip cease. This is desirable for reasons of luminous efficiency, and because such starting strip is not designed to constitute an efficient locus for primary emission of light.

Wherever the term positive column discharge is used in this specification, there is meant such discharge of normal current value and producing a useful amount of radiation, and this term does not apply to any minor positive column discharges taking place at substantially lower voltages and at relatively low current intensities.

With the gas discharge tube of this invention, an improved form of starting strip is employed, overcoming difficulties hitherto found in constructing such starting strip and locating it at the desired position within the tube. Furthermore this invention provides an arrangement wherein the effective resistance of substantially the entire surface of the starting strip to the establishment of excessive discharge therefrom is greatly increased, so that there will be available a greater potential for establishing the desired column discharge.

Another object of this invention is to provide, in a gaseous discharge tube, a starting device including a relatively wide strip of metal or other conducting substance, which can be fabricated as a discrete unit and which can be placed in the desired position within a tube, when the tube is assembled, such discrete construction being adapted to economical large scale production, in contrast to certain hitherto employed methods of constructing a starting strip, *in situ*, within the tube itself.

Another object of this invention is to provide in a positive column discharge lamp, a starting strip bearing upon at least a portion of the surface thereof a coating of insulating material whereby such strip tends to offer a higher effective resistance, over a given length, then does the positive column discharge, so that current will not tend to be diverted from the desired positive column discharge path.

A yet further purpose of this invention is to provide a positive column discharge tube, in which the difference between starting and operating voltages is greatly reduced from that hitherto found necessary.

Still another object of this invention is to provide a cold cathode positive column discharge tube having sufficient length so that its efficiency will be relatively high and yet possessing starting characteristics such that the voltage applied

thereto may be kept within an upper limit, below which special insulation of the so-called "high-voltage" type is not needed. Such an upper limit is often determined in practice by codes or safety regulations, a figure of 600 volts being usually placed as such limit.

A certain advantage of one form of this invention is that it provides a positive column discharge tube in which a plurality of conductive starting strips are so arranged as to present, as a whole, a relatively high resistance to gas discharge therefrom. Such effectively high resistance is due to the provision of a number of gaps between individual starting strips and between such strips and the tube electrodes, since this will result in virtually placing in series with one another the cathode fall occurring at each gap. This form of the invention allows the construction of a tube in which the positive column discharge may be made of greater length, and consequently having greater drop of potential thereacross than would otherwise be possible without the discharge being shunted by the starting strip, to a greater or lesser degree.

Other purposes and advantages of this invention will be apparent to those skilled in the art from the following description of several embodiments of this invention.

Reference is now made to the drawings hereunto attached, where

Fig. 1 is a perspective view of a tube embodying one form of this invention.

Fig. 2A is a cross-sectional view of the tube of Fig. 1.

Fig. 2B is a cross-sectional view of a tube embodying another form of this invention.

Fig. 3 is a single-end connected tube showing another form of this invention, and

Fig. 4 shows, partly schematically, an alternative form of this invention, using a divided starting strip.

Referring now to Figs. 1 and 2A, there is here shown an elongated tube 1, of suitable gas-confining material such as glass. This material is

chosen to be transparent to radiations having such wave lengths as are to be utilized externally. For example, the tube may be constructed of ultra violet transmitting glass or of quartz, if the radiations lie in the ultra violet portion of the spectrum. Suitable electrodes of the cold cathode type, 2, are shown at each end of the tube. Extending longitudinally of the tube, but terminating short of each electrode is a conducting strip 3. As shown in Fig. 2A, it is preferred that this strip extend for approximately 180 degrees around the internal periphery of the tube. However, strips extending over a greater or lesser angle may be employed without departure from this invention. Strip 3 may be formed of any suitable conducting material which will withstand the temperature and treatment incidental to the manufacture and operation of the tube. Such material should be capable of ready de-gasification and should not evolve gases during operation of the tube. For reasons hereinafter to be explained in detail, I prefer to make this strip of comparatively thin metal or alloy, possessing some degree of elasticity. Suitable materials include iron, nickel-plated iron, magnesium and aluminium, but this invention is not confined to the employment of these particular metals. The strip may be sprung into a semi-cylindrical form, as it is being inserted into the tube, or prior to such insertion therein. The elasticity of the

strip will then cause it to be pressed more or less

firmly against the portion of the tube wall covered thereby. It is, however, possible to use a relatively less elastic material for the strip and to provide a coating of adhesive material between the strip and the tube wall, in order that the strip shall remain in the proper position, or it is possible to mount or fasten the strip in place by any other means as long as the only conducting path to the electrodes is through the gas filling of the tube.

As known in the art, all portions of a starting strip do not act uniformly, and by the active portions of the strip are meant those upon which cathode glow discharges tend to be established.

In Fig. 2B there is shown a variant form 3' which the strip just described may assume. In this particular form, the apex of the V and extremities of the two arms of the V constitute three points of contact extending longitudinally along the tube wall. The tendency of the V to expand laterally may be used to hold the strip in place.

When a strip having an interior reflecting surface is employed, it is evident that radiations produced by the positive column discharge in the tube will pass in part directly through the relatively unobstructed portion of the tube wall opposite the reflecting strip. Radiations impinging upon the strip will be reflected therefrom and will also pass through the same transmitting portion of the tube wall.

Evidently the surface of the reflecting strip should be chosen of a nature to act as an efficient reflector for the particular wave lengths which are to be emitted from the tube.

For confining the positive column discharge to the proper path thereof, it has been found desirable that the surface of the reflecting strip which faces this path within the tube be covered with a layer of insulating material 4. If the material constituting the surface of the starting strip be metallic in nature, it may be desirable to place over it an outside layer of some material which is relatively translucent or reflecting, but which is also non-conducting. Many white materials such as aluminum oxide, magnesium oxide, or other metallic oxides, and the like, function both as a suitable reflecting surface and as a suitable insulator. A material such as aluminum oxide also functions well in cases where reflection of ultra violet radiations, as well as visible, is desired.

These materials are applied in the form of discrete particles, as indicated in Figs. 2A, 2B and 3, each particle, being impervious and insulative to the discharge, while the interstices between particles allow current flow to and from the strip. Any organic binder, initially used as a vehicle for the coating, is burned away prior to or during the tube exhaust, leaving the material in the desired form of discrete particles.

In the case of gas discharge tubes of the fluorescent type, the visible light proceeds from a material which is usually non-conducting and only somewhat transparent. Such phosphors may be used to cover the surface of the reflecting strip, in which case the material probably acts, not only as a light emitter, but also to a certain extent as a light reflector.

In certain embodiments of this invention, the longitudinal wall of the tube opposite such a strip coated with a phosphor is relatively transparent, and inversely related to the arc covered by the relatively opaque reflecting strip. As the

reflecting strip is made to extend more than 180 degrees, the light will be emitted throughout an arc correspondingly less than 180 degrees. This last described arrangement will in many cases eliminate the need for external reflectors. By my use of a separate strip bearing the phosphor, such type of lamp may be manufactured very simply, whereas it has been found very difficult to coat the internal wall of a tube over only a portion of the periphery thereof.

Measurements made upon a fluorescent type tube employing a reflecting strip covering approximately 180 degrees, and covered with a phosphor, showed a luminous output over approximately 180 degrees, of 33 units in comparison with 23 units obtained from a similar tube, drawing the same amount of electrical energy, but employing a phosphor distributed over the entire inner surface of the tube, according to the hitherto prevailing practice in the art.

It will be evident that for ease in replacement, it will be desirable that the starting strip be placed within the tube at a predetermined angular relationship to the contact making pins usually provided in pairs at both ends of the tube. This will ensure that, when a fixture or other device mounting the two sockets in which the tube is to be placed, has once been put in position, the reflecting strip will be found in the desired position relative to the direction in which the useful light output is to be radiated. In the case of direct lighting, this direction usually will be downward and no external reflector will be needed. In the case of indirect lighting, the direction usually will be upward or sidewise, but no shield between the light source and the eye will be needed because of the opaque strip in the lamp. In either case the strip serves as a reflecting surface or light source which cannot be reached by dust and dirt.

It is thought unnecessary to describe in detail the connection of a gas discharge tube to the power supply, via a transformer or similar inductive device. The following points, however, are of importance in discussing the problems solved by this invention. Such power supply transformer is preferably designed to exhibit poor regulation. Such transformers are well known in the gas tube art and may utilize a relatively high magnetic leakage arrangement, or other methods of obtaining such poor regulation may be employed. Since the transformer must afford, upon an open circuit, a potential sufficiently high to initiate the gas discharge, but also must be so arranged that, when the normal discharge current has once been established, the potential supplied to the tube electrodes will not exceed that necessary to maintain the normal current, it is evident that the difference between the starting and operating voltages of the transformer will be determined, to a great degree, by the characteristics of the tube. It is likewise apparent that, the lower the value at which this difference of potential may be established, the better will be the regulation of the transformer, and consequently the higher will be both power factor and efficiency of the combination of tube and transformer. All potentials mentioned in this specification are expressed in root mean square volts.

It is to be noted that this invention may be used with equal facility with tubes of either the hot or cold cathode type, inasmuch as the positive column conditions in the two types are independent of the type of electrode, and hence the

discharges are established by the starting conductors in exactly the same manner in either case.

Referring now to Fig. 3, there is here shown a bulb 10, provided at one end with a conventional type of screw base. The leads from electrodes 11 and 12 pass through the press 13 and connect to the external screw base. A partition or strip 14 extends from the press upwardly to a point near the other end of the bulb. This partition is shaped and sized to meet the internal walls of the bulb, so that the bulb is divided into two discrete compartments, open to one another only at the upper end of the bulb, and may be formed either of metal, as shown, or of insulating material such as glass or mica, suitably coated as later described. The sides of this partition are coated with a suitable insulating material 4, such as previously described, so that the partition will function as the improved starting strip of this invention. The discharge extends upwardly in one chamber, crosses the upper end of the bulb, and descends in the other chamber. If the partition be made of an insulating substance, then it may be first coated with a conducting material, and then with one of the insulating and preferably reflecting or translucent types of material previously described. Likewise, the phosphor, in the case of a wavelength conversion type of lamp, may be placed upon this partition, as also previously described.

In Fig. 4 there is shown a tube of the same general type as that shown in Fig. 1. However, in this case the starting strip is divided, at or near the center, so that there are really two starting strips, discrete from one another, and effectively operating in series. The general method of operation of this bulb is similar to that already described in connection with Fig. 1. However, the two starting strips, 31 and 32, present, together with the two electrodes, a total of three gaps, over which the cathode glow discharge must be initiated, before the eventual establishment of the positive column discharge. This would seem at first sight to be a disadvantage, in that it increases the needed starting voltage, since each gap will require at least approximately 100 volts in order to establish a discharge thereacross. However this form of construction of the tube has the advantage that the maximum length of the positive column discharge may be increased over the length possible when employing a single starting strip. This arises from the fact that, with increase in length of a single starting strip, a point is reached where the voltage required to initiate the positive column discharge will become so great that the strip will permit the full value of the normal discharge current to flow as a negative glow discharge from its surface without reaching the voltage required to initiate the positive column discharge. I have found improved results by making the two starting strips of unequal length, for example in a ratio of lengths of 39 to 46.

With the multiple starting strip employed in this particular form of structure of this invention, the total voltage drop across the gaps of the starting strips and electrodes will be raised to a point where the positive column may be considerably lengthened, relative to the length possible when only a single starting strip is employed. The following examples of measurements upon actual tubes serve to illustrate certain advantages secured by the use of one form of my invention.

With the prior art tubes, not employing a starting strip, the following values may be taken as illustrative. For a cold cathode tube having a bore of about 22 mm. and a positive column length of about 90 inches and an operating current of about 150 milliamperes, the terminal potential when operating will be found to be in the region of 450 volts. On the other hand, in order to cause the initiation of the positive column discharge, a potential in excess of 600 volts is usually required. Since the underwriters' regulations require electrical apparatus employing more than 600 volts to be constructed with special insulation of greater extent and cost than that allowable at voltages below this figure, it can be seen that the tube of this invention will present the further advantages that the cost and complexity of the auxiliary apparatus employed therewith, may be kept at a minimum. These values are understood to be illustrative, but represent actual measurements made upon such tube. While the foregoing discussion has applied to transformers, similar considerations apply to other inductive ballast devices.

When a tube having the same physical dimensions and the same operating current as that just described, was provided with a starting strip having two sections according to the embodiment of this invention shown in Fig. 4, actual measurements showed that a cathode glow discharge would appear at the tube electrodes with a terminal potential of 380 volts. At a potential in the neighborhood of 535 volts, the positive column discharge was initiated, upon which the terminal voltage immediately fell to the normal operating value of 450 volts. The respective values just given illustrate the advantage of voltage reduction secured by the use of this invention.

Among the novel advantages of that form of this invention which embodies a separable strip is the fact that the actual application of the insulating or fluorescent material does not have to take place within the relatively narrow confines of the glass tube. The strip is preferably coated before insertion in the tube, thus making possible the use of the spray gun, dipping, dusting, or other high-speed production methods not so readily applicable to coating the inside of glass tubes. These methods permit the use of fluorescent powder or pigments which do not have to be subjected to the prolonged grinding or ball-milling now customary in making suspensions for coating the inner surfaces of fluorescent lamps. The less the grinding of the fluorescent particles, the more efficient they are. Likewise, less care will be needed in applying this coating than is needed in applying it to an ordinary fluorescent lamp since excess thickness upon any portion of the strip will not give rise to uneven illumination of the bulb. I have found that coatings made from the usual fluorescent silicates may be as much as several thousandths of an inch in thickness and still be sufficiently permeable to the discharge to permit the negative glow to spread along the strip as desired to facilitate starting. Also the fluorescent materials may readily be applied in trade mark and decorative designs of different fluorescent colors, by means of silk screen reproduction methods for example.

It has been found that the coated starting conductors of this invention are less limited in the suitable range of gas pressures than are those strips having highly conducting surfaces. It is preferred to fill the bulbs of this invention at, or

slightly above, the gas pressure corresponding to the minimum positive column drop under normal conditions of operation for that particular transverse cross-sectional area of positive column. This optimum gas pressure is well known for conventional bulbs, and is not materially altered by the addition of the coated conductor of this invention. In a bulb having a 25 mm. inside diameter, for example, it has been found that 3 mm. of argon, or argon and neon, gas pressure operates satisfactorily. The coated conductor also functions according to the previous description if the pressure is varied from approximately 1 mm. to 5 mm. of such gases with the additional presence of mercury vapor.

While there have been described certain non-limiting forms of this invention, other forms will be apparent to those skilled in the art, and the scope of this invention is limited only by the hereunto appended claims.

What is claimed is:

1. In an elongated positive column discharge tube containing an ionizable gas, two electrodes positioned within said tube, at the respective ends thereof, a trough-shaped metallic starting strip positioned within said tube, partly surrounding and extending longitudinally a substantial distance along the path of the discharge, and a coating of insulating material in the form of discrete particles, each particle being relatively impermeable and insulative, said insulating coating covering substantially the entire active interior surface of said strip and being porous, to allow a cathode glow discharge to pass through the interstices between said particles, and yet offering a material electrical resistance, whereby current flow via said starting strip is minimized both before and after establishment of the positive column discharge, and whereby the outer surface of said strip reduces light emission from a portion of said tube.

2. A device according to claim 1, wherein said metallic strip is constituted by a plurality of discrete sections, separated electrically from one another by gaps.

3. A tube according to claim 2, in which said starting strips are of unequal length, whereby starting is facilitated.

4. A tube according to claim 3, in which said starting strips are two in number and the length of one strip is to the length of the other strip substantially in the ratio of 39 to 46.

5. A device according to claim 1, wherein one side of said strip has an area not substantially less than the longitudinal cross-sectional area of said positive column discharge.

6. A positive column gas discharge tube, including an elongated envelope containing an ionizable gas, a pair of spaced electrodes sealed within said envelope at the respective ends thereof, a metallic trough-shaped strip formed of conductive material, extending within said tube for a substantial portion of the path of the positive column discharge between said electrodes and partly surrounding said path, said strip being spaced apart from both electrodes and bearing at least upon the side thereof facing said

discharge a substantially complete covering of a porous material formed of discrete particles, each particle being relatively impermeable and insulative, said coating acting by its presence to give said strip a relatively rapidly rising voltage characteristic when said strip functions as a cathode, thereby permitting establishment of a starting cathode glow discharge but minimizing the current thereof, said cathode glow discharge taking place through the interstices between said particles, and whereby said strip reduces light emission from said tube at a portion thereof back of said strip.

7. A fluorescent lamp including an elongated glass tube having therein a filling of at least one inert ionizable gas and mercury vapor, two main discharge electrodes spaced apart within and at the ends of said tube, so that there is formed therebetween, upon excitation of the lamp, a luminous positive column discharge circumferentially defined by the wall of the tube, a metallic trough-shaped starting strip partly surrounding the discharge space and extending longitudinally a substantial distance along the discharge path, and having upon the active side thereof a coating of a porous fluorescent insulating material formed of discrete particles, each particle being relatively impermeable and insulative, the length and area of said strip exceeding that sufficient to shunt current from the positive column during continued operation of the lamp in the absence of said coating, whereby said strip reduces light emission from the tube in a rearward direction and passes therethrough substantially no current during the time when said positive column discharge exists, due to the presence upon said strip of said coating, said coating being sufficiently permeable to allow the establishment therethrough of a starting cathode glow discharge, said discharge taking place through the interstices between said particles.

8. Device according to claim 1, wherein said tube is formed as an elongated cylinder and said starting strip has a semi-cylindrical configuration whereby said strip can be separately formed and inserted into said tube as a discrete element lying closely adjacent to a portion of the internal longitudinal wall of said tube.
